UNITED STATES PATENT OFFICE

ROBERT M. PHINNEY, OF ROCHESTER, NEW YORK, ASSIGNOR TO GENERAL RAILWAY SIGNAL COMPANY, OF ROCHESTER, NEW YORK

TRAIN-DISPATCHING SYSTEM FOR RAILROADS

Application filed September 21, 1929. Serial No. 394,240.

This invention relates to train dispatching systems, and more particularly to means for giving a plurality of conflicting indications over the same line circuit by direct current.

In train dispatching systems of the type shown in the application of F. L. Dodgson, Ser. No. 187,508 filed April 29, 1927, it is sometimes found necessary to give more indications of occupancy of track circuits than can be accomplished over the control wires for controlling switch machines and signals, and the present invention relates to an arrangement enabling two conflicting continuously effective signalling indications to be given over the same line circuit simultaneously. These indications should be of continuous nature so that not only the instant of occupancy of a track circuit is indicated but the instant of clearing of such track circuit is also indicated. In accordance with the present invention it is proposed to give one indication by the transmission of current of positive polarity to give another indication by the transmission of current of negative polarity and to simultaneously give both of these indications by transmitting alternate positive and negative impulses over the line circuit. Another object of the present invention resides in the provision of means for momentarily sounding an alarm for each important change in signal indications transmitted in accordance with the present invention.

Other objects, purposes, and characteristic features of the present invention will in part be obvious from the accompanying drawings and in part be pointed out hereinafter.

In describing the invention in detail reference will be made to the single drawing conventionally illustrating one embodiment of the present invention, in which the portion in the rectangle signifies the apparatus in the dispatcher's office and the rest of the drawing shows the apparatus at a distant passing siding.

The invention has been shown applied for indicating the occupancy of two track circuits, one of which is on the main track and

the other of which is on the side track of a passing siding PS. It should however be understood that the invention is equally applicable for indicating positions of switches, signals, derails and the like. The rails of the railway track have been shown at 1, divided into track sections by insulating joints 2, of which the main track section includes a track circuit having a track battery 3 and a track relay T, and of which the side track 55 is provided with a track circuit having a track battery 4 and a track relay T¹. At the location of the passing siding PS are provided interlocked relays X and Y, conveniently called oscillating relays, in that they are so interlocked that energization of one of these relays effects deenergization of the other, so that they will continue to pick up and drop through the medium of their interlocked circuits when current is applied 60 thereto.

In the dispatcher's office is provided a miniature track layout which diagrammatically illustrates the distant passing siding PS by the miniature passing siding ps, and in practice the entire railroad to which the invention is applied is reproduced in miniature in the dispatcher's office in the same way. Adjacent the main track of the miniature passing siding ps is shown an indicating lamp MI, 75 which when lighted manifests occupancy of the main track of the passing siding PS, and similarly the indicating lamp SI adjacent the side track of the miniature track layout illustrates, when illuminated, occupancy of the 80 side track of the passing siding PS. The dispatcher's office apparatus also includes a line relay LR of the biased-to-neutral polar type together with slow-acting relays SR and MR, and an audible signal or bell BL. It is believed that the invention will be more readily understood by considering the operation of the system conventionally illustrated, and such operation will now be taken up.

Operation.—Let us assume that a train 95 enters the main track of a passing siding PS. As soon as this train treads upon the track circuit containing the track relay T this track relay T will be deenergized and its back contact 9 will close the following circuit for the 100

line relay LR:—beginning at the positive terminal of the battery 10, wires 11 and 12, back contact 9 of the track relay T, wires 13 and 14, front contact 15 of the track relay T¹, wire 16, back contact 17 of the relay X, line wire 18, winding of the line relay LR, wires 19, C and 20, to the midpoint of battery 10. The flow of current in this circuit causes the contact 21 of the line relay LR to move to the right, thereby closing the following circuit 5 for the main indicating relay MR:—beginning at the terminal B of a suitable battery, wire 22, contact 21 of the relay LR, wires 23 and 24, winding of the relay MR, to the common return wire C connected to the other 10 terminal of said battery.

Similarly, the following circuit for the bell BL is closed:—beginning at the terminal B, wire 22, contact 21 of the relay LR, wires 23 and 25, back contact 26 of the relay MR, 20 wires 27 and 28, winding of the bell BL, to common return wire C. It will be noted that the circuit just traced will only be closed momentarily in that it will again be opened at the contact 26 as soon as the main relay MR 25 assumes its attracted position.

After this momentary sounding of the bell BL the following circuit for the main indicating lamp MI is closed:—beginning at the terminal B of a suitable battery, front contact 30 of the relay MR, wire 31, indicating lamp MI, to the other terminal C of said battery. Obviously, when the train passes off of the main track of the passing siding PS the track 35 relay T is again energized, the circuit for the line relay LR is broken, the main relay MR is deenergized and the indicating lamp MI is extinguished.

Let us now assume that the side track of the 40 passing siding PS is occupied and that the track relay T¹ assumes its retracted position. Under this condition the following circuit for the relay LR is closed:—beginning at the negative terminal of the battery 10, wire 47, 45 contact 15 of the track relay T¹, in its retracted position, wire 16, back contact 17 of the relay X, line wire 18, winding of the relay LR, wires 19, C and 20, to the midpoint of battery 10. The completion of this circuit causes the line relay LR to be moved to its left-hand position in which the following circuit for the relay SR is closed:—beginning at the terminal B, wire 22, contact 21, wires 32 and 33, winding of the relay SR, to the other terminal C of said battery. Similarly, the following circuit for the bell BL is closed:—beginning at the terminal B, wire 22, contact 21 of the relay LR, wires 32 and 34, back contact 35 of the relay SR, wires 36 and 28, winding of the bell BL, to the other terminal C of said battery. It will be noted that the circuit for the bell BL is only momentarily closed in that the attraction of the armature of relay SR causes the contact 35 65 to open this circuit.

With the relay SR assuming its energized position the following circuit for illuminating the lamp SI is closed:—beginning at the terminal B of a suitable battery, front contact 48 of the relay SR, wire 49, indicating lamp SI, 70 to the other terminal C of said battery. Obviously, clearing of the track circuit of the side track of the passing siding PS will cause the track relay T¹ to pick up, thereby again extinguishing the lamp SI, for obvious 75 reasons.

Let us now assume that both of the tracks of the passing siding PS are occupied, either simultaneously or one at a later time than the other. With both of the track relays T and 80 T¹ assuming their retracted position the following circuit is closed for the oscillating relay X:—beginning at the positive terminal of the battery 10, wires 11 and 12, back contact 9 of the track relay T, wires 13, back contact 40 of the track relay T¹, wires 41 and 42, back contact 43 of the relay Y, wire 44, winding of the relay X, wires 45 and 46, to the negative terminal of the battery 10. 85

The closure of this circuit causes the relay X to be energized, and as soon as this relay X assumes its energized position the contact 50 of this relay X closes, thereby closing the following circuit for the relay Y:—beginning at the positive terminal of the battery 10, 90 wires 11 and 12, back contact 9 of the track relay T, wire 13, back contact 40 of the track relay T¹, wires 41 and 51, contact 50 of the relay X, wire 52, winding of the relay Y, wires 53 and 46, to the negative terminal of the battery 10. Obviously, energization of this relay Y causes it to pick up its contact 43 thereby opening the energizing circuit of the relay X, so that the relay X again assumes 95 its retracted position, and in so doing causes the relay Y to be deenergized, which when it assumes its deenergized position will again energize the relay X. In other words, these relays will continue to bob up and down, so to speak, by reason of having their energizing circuits alternately made and broken as is apparent from the circuits for these relays just traced. 100

With the relay X repeatedly picking up and dropping, its contacts 17 will alternately 115 apply positive and negative current to the line relay LR in the dispatcher's office, through the branch portion 11—56 and 47—15—16, respectively. This flow of alternate positive and negative impulses 120 through the winding of the line relay LR causes the contact 21 of this relay LR to repeatedly energize the relays SR and MR. Since these relays SR and MR are slow-dropping, as conventionally shown by the shaded portion thereof, these relays SR and MR will both be maintained in their attracted position, thereby closing their respective contacts 30 and 48, and thereby illuminating the indicating lamps MI and SI, indicating occu- 125 130

pancy of the main track and side track of the passing siding PS. It will be readily understood that if one of these trains passes off of its track circuit that the oscillation of the 5 relays X and Y will be discontinued and current of the proper polarity corresponding to that of the track circuit still occupied will be transmitted to the line relay LR, so that one of the lamps MI or SI will be extinguished 10 and the other will remain illuminated. Also, it will be understood that the bell BL is momentarily sounded as each of the relays SR and MR assumes its attracted position, and that this bell is not sounded when these relays 15 again assume their attracted position.

Although the present invention has been shown applied to a system wherein it is proposed to give two conflicting indications over the same line circuit by the use of direct 20 current, it should be understood that two independent controls can be carried on even though these controls are unrelated and must at times be applied in over-lapped relation. For instance, if desired, contacts 9 and contacts 25 40 and 15 may be applied to control levers and the relays SR and MR may be used as control relays to control switch machines, derails, signals, and the like. Also, the system is useful in interlocking yards, and is 30 useful for controlling an outlying switch, and the scope of the invention is not such as to limit its application to train dispatching only.

Having thus shown and described one 35 rather specific embodiment of the present invention, it is desired to be understood that this has been done for the purpose of facilitating disclosure of the invention rather than illustrating the exact circuit arrangement preferably employed in practicing the invention 40 or the scope of the invention, and that various changes, modifications and additions, may be made to adapt the invention to the particular problem encountered in practicing the same, all without departing from the 45 spirit or scope of the invention, or the idea of means underlying the same, except as demanded by the scope of the following claims.

I claim:

1. In a system for indicating the progress 50 of trains at a distant point; the combination with two distant track sections of a railway track and a local dispatcher's office; of an indicator at said dispatcher's office for each of said track sections; and means for rendering 55 said indicators effective in response to occupancy of said sections comprising; a line circuit connecting said dispatcher's office and said distant point including a polar relay at said dispatcher's office, means at said 60 dispatcher's office for rendering one of said indicators active when said polar relay assumes one polar position, for rendering the other of said indicators active when said polar relay assumes the other polar position and rendering both of said indicators active when 65

said polar relay oscillates from one polar position to the other polar position, and means at said distant point for applying electrical energy of one polarity to said line circuit when one of said sections is occupied applying energy of the opposite polarity when the other section is occupied and alternately applying energy of one polarity and then of the other polarity when both of said sections are occupied.

2. In a system for indicating the progress of trains at a distant point; the combination with two distant traffic controlled devices of a railway track and a local dispatcher's office; of an indicator at said dispatcher's office for each of said traffic controlled devices; and means for rendering said indicators effective in response to a change in said devices comprising; a line circuit connecting said dispatcher's office and said distant point including a polar relay at said dispatcher's office, means at said dispatcher's office for rendering one of said indicators active when said polar relay assumes one polar position, for rendering the other of said indicators active when said polar relay assumes the other polar position and rendering both of said indicators active when said polar relay oscillates from one polar position to the other polar position, and means at said distant point for applying electrical energy of one polarity to said line circuit when one of said devices is operated applying energy of the opposite polarity when the other device is operated and alternately applying energy of one polarity and then of the other polarity when both of said devices are operated.

3. In a system for indicating the progress of trains at a distant point; the combination with two distant track sections of a railway track and a local dispatcher's office; of an indicator at said dispatcher's office for each of said track sections; and means for rendering said indicators effective in response to occupancy of said sections comprising; a line circuit connecting said dispatcher's office and distant point including a direct current polar relay at said dispatcher's office, means at said dispatcher's office for rendering one of said indicators active when said polar relay assumes one polar position, for rendering the other of said indicators active when said polar relay assumes the other polar position and rendering both of said indicators active when said polar relay oscillates from one polar position to the other polar position, and means at said distant point for applying direct current of one polarity to said line circuit when one of said sections is occupied applying direct current of the opposite polarity when the other section is occupied and alternately applying direct current of one polarity and then of the other polarity when both of said sections are occupied.

4. In a system for indicating the progress

of trains at a distant point; the combination, with two distant traffic controlled devices of a railway track and a local dispatcher's office; of an indicator at said dispatcher's office for 5 each of said traffic controlled devices; and means for rendering said indicators effective in response to a change in said devices comprising; a line circuit connecting said dispatcher's office and said distant point including a direct current polar relay at said dispatcher's office, means at said dispatcher's office for rendering one of said indicators active when said polar relay assumes one polar position, for rendering the other of said 10 indicators active when said polar relay assumes the other polar position and rendering both of said indicators active when said polar relay oscillates from one polar position to the other polar position, and means 15 at said distant point for applying direct current of one polarity to said line circuit when one of said devices is operated applying direct current of the opposite polarity when the other device is operated and alternately applying direct current energy of one polarity 20 and then of the other polarity when both of said devices are operated.

5. In a system for indicating the progress of trains at a distant point; the combination, 30 with two distant track sections of a railway track and a local dispatcher's office; of an indicator for each of said track sections; and means for rendering said indicators effective in response to occupancy of said sections comprising; a line circuit connecting said dispatcher's office and said distant point including a polar relay at said dispatcher's office, two slow dropping relays associated with said polar relay one of 35 which is energized when said polar relay assumes one polar position and the other of which is energized when said polar relay assumes the other polar position, and one of said indicators being controlled by one of said slow dropping relays and the other of said indicators being controlled by the other slow dropping relay, and means at said distant point for applying electrical energy of one polarity to said line circuit when one of said sections is occupied applying energy of the opposite polarity when the other section is occupied and alternately applying energy of one polarity and then of the other polarity when both of said sections 40 are occupied.

55 6. In a system for indicating the progress of trains at a distant point; the combination, with two distant traffic controlled devices of a railway track and a local dispatcher's office; of an indicator for each of said traffic controlled devices; and means for rendering said indicators effective in response to a change in said devices comprising; a line circuit connecting said dispatcher's office and said distant point including a

polar relay at said dispatcher's office, two slow-dropping relays associated with said polar relay one of which is energized when said polar relay assumes one polar position and the other of which is energized when said polar relay assumes the other polar position, and one of said indicators being controlled by one of said slow dropping relays and the other of said indicators being controlled by the other slow-dropping relays, and means at said distant point for applying electrical energy of one polarity to said line circuit when one of said devices is operated, applying energy of the opposite polarity when the other device is operated and alternately applying energy of one polarity and then of the other polarity when both of said devices are operated.

7. In a system for indicating the progress of trains at a distant point; the combination, 70 with two distant track sections of a railway track and a local dispatcher's office; of an indicator for each of said track sections; and means for rendering said indicators effective in response to occupancy of said sections comprising; a line circuit connecting said dispatcher's office and said distant point including a direct current polar relay at said dispatcher's office, two slow-dropping relays associated with said polar relay one of which is energized when said polar relay assumes one polar position and the other of which is energized when said polar relay assumes the other polar position, and one of said indicators being controlled by 75 one of said polar relays and the other of said indicators being controlled by the other polar relay, and means at said distant point for applying direct current of one polarity to said line circuit when one of said sections is occupied, applying direct current of the opposite polarity when the other section is occupied and alternately applying direct current energy of one polarity and then of the other polarity when both of said sections 80 are occupied.

8. In combination; a line circuit; two slow acting relays at one end of said line circuit; two circuit closing devices at the other end of said line circuit; a battery associated with said circuit closing devices to enable current of either polarity to be applied to said line circuit; and means including a polar relay to effect energization of one, the other, both or neither of said slow acting relays in response to closure of one, the other, both or neither of said circuit closing devices.

9. A system for transmitting two continuing distinctive indications of traffic over a single circuit comprising; a single line circuit connecting a local office and a distant point; means for energizing said line circuit with current of one polarity under one traffic condition, energizing said line circuit with current of the opposite polarity under 125

another traffic condition and for energizing said line circuit alternately with currents of opposite polarities when both of said traffic conditions exist; and means at said local office for indicating the condition of energization of said line circuit.

10. A system for transmitting two continuing distinctive indications of traffic over a single circuit comprising; a single line circuit connecting a local office and a distant point; means for energizing said line circuit with current of one polarity under one traffic condition, energizing said line circuit with current of the opposite polarity under another traffic condition and for energizing said line circuit alternately with currents of opposite polarities when both of said traffic conditions exist; two indicators at said local office one of which is active when said line circuit is energized by current of one polarity, the other of which is active when said line circuit is energized by current of the other polarity and both of which are active if said line circuit is alternately energized with currents of opposite polarities.

11. A system for transmitting two continuing distinctive indications of traffic over a single circuit comprising; a single line circuit connecting a local office and a distant point; means for energizing said line circuit with current of one polarity under one traffic condition, energizing said line circuit with current of the opposite polarity under another traffic condition and for energizing said line circuit alternately with currents of opposite polarities when both of said traffic conditions exist; a three-position polar relay in said line circuit at said office, two slow acting relays one energized for each of the two polar positions of said polar relay, and an indicator for each slow acting relay rendered active so long as its associated slow acting relay assumes its energized position.

12. A system for transmitting two continuing distinctive indications of traffic over a single circuit comprising; a single line circuit connecting a local office and a distant point; means for energizing said line circuit with current of one polarity under one traffic condition, energizing said line circuit with current of the opposite polarity under another traffic condition and for energizing said line circuit successively with currents of opposite polarities when both of said traffic conditions exist; and means at said local office for indicating the condition of energization of said line circuit.

In testimony whereof I affix my signature.
ROBERT M. PHINNEY.
